METHOD OF MOUNTING PLASTER LATH

Filed Jan. 8, 1930

INVENTOR

J.F. Makowski

BY *Henry J. Lederle*

ATTORNEY

UNITED STATES PATENT OFFICE

JOHN F. MAKOWSKI, OF OAKLAND, CALIFORNIA, ASSIGNOR TO FIREPROOF WALL COMPANY, A CORPORATION

METHOD OF MOUNTING PLASTER LATH

Application filed January 8, 1930. Serial No. 419,336.

This invention relates to the building art, and particularly to wall construction wherein lathing material is mounted against vertical studding for forming the key base for 5 plaster and the like.

The present specification describes the invention as particularly applied to the application of plaster wall board or plaster lathing strips to the studs, but in actual practice it can 10 be applied to any form of lathing material to which it may be found adaptable.

In the erection of walls, particularly partition walls in which the lathing material of the character described is used, it is quite common to first erect a series of equally spaced 15 supporting studs, which are preferably small channel irons usually not greater than from one-half to three-fourths inches in width. The lathing strips are usually from twelve to eighteen feet long and from six to twelve 20 inches wide, and in applying these strips against the stud it has been the usual practice to have the ends of the strips cut off at right angles to the length thereof and the abutting 25 ends or joints are put together adjacent the studs.

Due to the narrow width of the studs it has been a very difficult proposition to make a 30 secure joint and one which will not tend to collapse under pressure.

The present invention therefore embodies a means for forming the joints between the lathing strips at the studs in such a manner as to give them a secure bearing surface and at the 35 same time render it an easy matter to apply the lathing strips to the studs and fasten them thereto in a rapid and effective manner.

A further object of the invention is to produce a simple and inexpensive device and yet 40 one which will be exceedingly effective for the purpose for which it is designed.

These objects I accomplish by means of such structure and relative arrangement of parts as will fully appear by a perusal of the 45 following specification and claims.

The figure of the drawing is a perspective view of a fragmentary portion of a wall showing my improved method of applying lathing strips to the studs thereof.

50 Referring now more particularly to the

characters of reference on the drawings, the numeral 1 designates the studs which are set vertically in spaced relation and adapted to act as supports for the lathing strips 2. In carrying out my improved invention instead 55 of having the abutting edges of the lathing strips cut at right angles to the length thereof I cut them diagonally or angularly in any one of the forms shown in the drawings, as at 3. Thus when the ends of the strips are abutted together adjacent the supporting studs the joints between the strips would center approximately on the face of the stud and bear down on same, but at the same time project slightly to each side thereof, as shown at 4. 60 By reason of these projections clips or other fastening means 5, preferably of the type shown in my copending application for patent, Serial No. 406,583 filed November 12, 1929, may be then employed to fasten the 65 lathing strips to the studs and can be very effectively employed to do this by reason of the adequate surface provided on each side of the stud against which the clips may bear.

It will be apparent that this clip construction could not be very successfully applied in the event the lathing strips were abutted edge to edge along the length of the stud as has heretofore been the custom, since due to the narrow width of the stud it would be 70 hard to secure a bearing surface on both abutting strips against the surface of the stud, but by this overlapping construction now shown this can be very advantageously 75 taken care of.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. The combination with a supporting 100 stud, of lath strips laid thereagainst, the ad-

adjacent ends of the strips forming a joint the upper and lower ends of which lie on opposite sides of the stud, and means mounted with the stud and crossing the joint intermediate its ends to hold the strips in contact with the face of the stud.

2. The combination with a supporting stud, of lath strips laid thereagainst, the adjacent ends of the strips forming a joint the upper and lower ends of which lie on opposite sides of the stud, and clips mounted with the stud and crossing the joint intermediate its ends to hold the strips in contact with the face of the stud.

3. The combination with a supporting stud, of lath strips laid thereagainst, the strips having their adjacent ends forming a joint crossing the face of the stud at an angle thereto, and means mounted with the stud and crossing the joint intermediate its ends to hold the strips in contact with the face of the stud.

In testimony whereof I affix my signature.
JOHN F. MAKOWSKI.
